UNITED STATES PATENT OFFICE.

GEORGE W. HOYT, OF CHICAGO, ILLINOIS.

DESIGN FOR A GARMENT-SUPPORTER LOOP.

SPECIFICATION forming part of Design No. 24,234, dated April 23, 1895.

Application filed February 21, 1895. Serial No. 520,282. Term of patent 14 years.

To all whom it may concern:

Be it known that I, GEORGE W. HOYT, a citizen of the United States, residing at Chicago, in the county of Cook and State of Illinois, 5 have invented and produced a new and original Design for Garment-Supporter Loops, of which the following is a specification, reference being had to the accompanying drawings, showing a part thereof.

10 Figure 1 represents a side elevation of a garment-supporter loop showing my design. Fig. 2 is an edge view of the same.

The leading feature of my design consists in a scalloped surface, the outlines of which 15 will fall entirely within the inner circular outline A or circumference in the center of the expanded portion of the loop.

B is the loop which is of the general contour shown in the drawings.

20 C is the slot through which the tape or other webbing is secured.

D is the contracted lower portion of the loop of the curved outline as shown, and E are op-

positely formed protuberances of graceful design in the exterior of the device. The irregular outline of the scalloped surface falls within the inner expanded portion of the loop, thus presenting to the eye the combined effect of a smooth circular outline and a scalloped outline concentrically within the former. 25

I do not desire to claim a supporter loop of this character with scalloped exterior edges around the expanded or upper portion of the loop, nor a garment loop in which both the inner and outer edges of the expanded portion 30 are scalloped.

What I claim is—

The design for a garment supporter loop, substantially as shown and described.

In testimony whereof I affix my signature 40 in the presence of two witnesses.

G. W. HOYT.
